UNITED STATES PATENT OFFICE.

JEFFREY T. FERRES, OF ANDERSON, INDIANA, ASSIGNOR TO J. W. SEFTON MANUFACTURING COMPANY, OF ANDERSON, INDIANA, A CORPORATION OF INDIANA.

BUILDING CONSTRUCTION.

No. 892,145.

Specification of Letters Patent.

Patented June 30, 1908.

Application filed September 15, 1905. Serial No. 278,615.

To all whom it may concern:

Be it known that I, JEFFREY T. FERRES, a citizen of the United States, residing at Anderson, in the county of Madison and State 5 of Indiana, have invented certain new and useful Improvements in Building Construction, of which the following is a specification.

My invention has relation to building construction, more particularly frame house 10 construction, in which it is required or desired to employ suitable means, such as paper or paper board for providing dead air spaces between the sheathing and lathing.

The object of my invention is to provide a 15 suitable board of such construction and arrangement as to form such air spaces between the lathing and sheathing and to effectually seal one from the other, and to maintain such conditions notwithstanding changes in 20 temperature.

Heretofore, when paper board, for instance, has been employed between the sheathing and lathing, it has been made of the same width as the distance between the studding, 25 serving merely as a lining, with the result that even though such board was originally fitted tightly, it would in time permit the passage of air from one side of the board to the other and such condition would result, of 30 course, from changes in temperature. According to my invention, I overcome these difficulties by providing a board, such as a corrugated paper board of a width greater than the distance between the studding, so 35 that when such board is in place it assumes a curved form with one perpendicular edge bearing against a studding and also preferably against the sheathing and always tending to keep the joint closed at this point, the 40 other perpendicular edge being secured at a point towards the outer edge of an adjacent studding, by which means each space between adjacent studding, divided into two 45 separate dead air spaces, is closed one from the other by the paper board and kept sealed one from the other under all varying conditions of weather and of shrinkage in the 50 wood of which the building is composed or in the paper between the studding. Moreover, 55 by the employment of corrugated paper board, I am enabled to provide an additional dead air space, which is present in the body of the paper board itself, inasmuch as the same, being a corrugated board, has a series of longitudinal air spaces formed between the facing strips of such board.

In the drawing Figure 1 is a side elevation of a portion of a wall exhibiting my paper board in place between the studding, Fig. 2 a horizontal section of such wall and Fig. 3 60 sections representing modifications of my invention.

As herein shown, the wall comprises essentially the studding A, sheathing B and the lathing C. The board which, in the present 65 instance and by preference, is double-faced corrugated paper board, marked D, is formed in strips of a width greater than the distance between two adjacent studdings, with the result that when one perpendicular edge 70 thereof is secured at or near the outer end of one of the studding, the board will assume a curved form with its other perpendicular edge resting or bearing against the other studding with some pressure, all as illustrated 75 in Fig. 2. As herein shown, the edge of the board which is fixed or anchored, is secured to the sheathing by tacks d, although the exact means for and place of attachment herein shown are not essential. The other 80 perpendicular edge of the paper board is kept in place within the space between the studding in suitable manner, as by means of the tacks or buttons c, which are driven through the edge of the paper and into the sides of 85 the studding adjacent such board thereby holding such edge in place. It will be understood after this description that owing to the greater width of the board as compared with the width or distance between the studding, 90 such board must necessarily assume a curved form with its edges bearing with some pressure against the sides of its adjacent studding, with the result that the air space between 95 two adjacent studding is divided into two dead air spaces E and F, which are effectually sealed one from the other under all conditions and at all temperatures, it being evident that upon any expansion or contraction of the parts of the wall or of the 100 board, the latter will maintain the sealing action. Moreover, as hereinbefore suggested, the corrugated board itself forms dead air spaces separate from the spaces E and F.

The strips of paper board may be made of 105 any desired length, but when the ordinary commercial lengths are employed, which are of course less than the height of the wall, a plurality of such strips may be employed and the same may be overlapped, an upper strip 110 overlapping a lower strip, viewed from the inside of the building, as illustrated in Fig. 1.

The construction or arrangement of the paper board as above described is the preferable one but if desired such board may partake of other forms and may be arranged or secured between the studding in other ways. For instance in Fig. 3 I have represented two of such modifications, the left hand board G is bent at its perpendicular edges to form the flanges g which are fastened by means of tacks to inner adjacent faces of the studding as clearly illustrated in said figure. The right hand board H is curved throughout its width with its perpendicular edges secured to the studding towards the outer edges thereof by means of the tacks h passing diagonally through such perpendicular edges of the board and into the studding, all as clearly illustrated in the right hand half of Fig. 3.

If desired the paper board may be treated with a suitable substance such as a solution of silicate of soda for the purpose of rendering the board moisture proof as well as fire proof.

I claim:

1. In building construction, the combination, with the studding of a building, of board of flexible material arranged to span the spaces from stud to stud in curved form; substantially as described.
2. In building construction, the combination, with the studding of a building, of a single sheet of paper board arranged to span the space between adjacent studs in curved form; substantially as described.
3. In building construction, the combination, with the studding of a building, of paper board arranged to span the spaces from stud to stud in curved form, both perpendicular edges of the paper board being fixed stationarily in the space between the studs and adapted to keep the air space on the opposite sides of the board sealed; substantially as described.
4. In building construction, the combination, with the studding of a building, of paper board arranged to span the spaces from stud to stud in curved form, one perpendicular edge of the paper board being

fixed stationarily in the space between the studs and the opposite edge bearing against the side of its adjacent stud, and means co-operating with said last named edge of the paper board to hold the latter to the stud; substantially as described.

5. In building construction, the combination, with the studding of a building, of paper board arranged to span the spaces from stud to stud in curved form, one perpendicular edge of the paper board being secured to such sheathing adjacent one stud and the opposite edge bearing against the next adjacent stud; substantially as described.

6. In building construction, the combination, with studding or the like and with the sheathing thereof, of paper board arranged to span the spaces between adjacent studs in curved form, one perpendicular edge of the paper board being secured to such sheathing adjacent one stud and the opposite edge bearing against the next adjacent stud, and tacks for securing the other perpendicular edge of the board to the last named stud; substantially as described.

7. In building construction, the combination, with the studding of the building, of a series of paper board overlapping each other and arranged perpendicularly to span the spaces in curved form from stud to stud between such studding, said boards being of a greater width than the distance between the studding and crowded into place in such curved form; substantially as described.

8. In building construction, the combination, with the studding, of a strip of corrugated paper board arranged perpendicularly to span the spaces in curved form from stud to stud between the studding, both perpendicular edges of the board being anchored between the studding; substantially as described.

JEFFREY T. FERRES.
